STEPHEN J. MILLER, OF DANBURY, CONNECTICUT

HAT FLANGING APPARATUS

Application filed May 3, 1929. Serial No. 360,075.

This invention relates to hat flanging machines.

One of the objects thereof is to provide a hat flanging machine adapted to operate upon the brim of a hat, efficiently and determinately, to give to said brim its final shape in conformity with the style of the flanging block employed therefor. Another object is to provide a brim flanging machine of practical construction and efficient action adapted completely to flange a hat in a single operation. Another object is to provide such a machine which is conveniently operated and readily adapted to varying sizes and shapes of hats. Other objects will be in part obvious and in part pointed out hereinafter.

The invention accordingly consists in the features of construction, combinations of elements and arrangements of parts which will be pointed out in the following description and the scope of the application of which will be indicated in the appended claims.

In the accompanying drawings in which is shown one of various possible embodiments of this invention,

Figure 1 is a cross section taken longitudinally through my flanging machine, showing the upper flanging iron in cross section in its initial forward position upon the brim of a hat, at which time the weight arm will be thrown to position A.

Fig. 2 is a side elevation of the machine, showing the parts in the position they will assume at a more advanced stage in the traverse of the flanging mechanism;

Fig. 3 is a view taken on line 3-3 of Fig. 1, showing certain parts in cross section;

Fig. 4 is a view taken on line 4-4 of Fig. 1, showing the pulley shaft in cross section;

Fig. 5 is a cross section taken on line 5-5 of Fig. 1;

Fig. 6 is a cross section taken on line 6-6 of Fig. 1;

Fig. 7 is a top plan view;

Fig. 8 is a section on line 8-8 of Fig. 1;

Fig. 9 is a section on line 9-9 of Fig. 1;

Fig. 10 is a section on line 10-10 of Fig. 1;

Fig. 11 is a sectional view of a modified

form of lower flanging iron;

Fig. 12 is a front elevation of said modification;

Fig. 13 is a section taken on line 13-13 of Fig. 10;

Fig. 14 is a rear elevation of the lower flanging iron, as shown in Fig. 1;

Fig. 15 is a section on line 15-15 of Fig. 14;

Fig. 16 is a plan view of the lower flanging iron, showing the shoe and body detached;

Fig. 17 is an end elevation of the shoe;

Fig. 18 is a cross section taken on line 18-18 of Fig. 16, showing the parts assembled and the shoe in end elevation; and

Fig. 19 is a side elevation of the iron holding mechanism and table support therefor, showing the relative position of the parts at a time when the iron has nearly completed its traverse of the hat brim.

Similar reference characters refer to similar parts throughout the views of the drawings.

Referring now to Figs. 1 and 2 of the drawings in detail, there is shown a frame 10, and mounted thereon an upright bearing 11, in which is rotatably supported a vertical shaft 12, having formed integral therewith at its upper end a cam plate 13, provided with a downwardly turned wall 14. This wall has uniformly spaced inner and outer camming surfaces, and has a peripheral outline designed in substantial conformity with the oval shape of the head opening of a hat (see Fig. 8.)

Shaft 12 is slowly rotated through the engagement of a bevel gear 15, rigidly mounted at its lower end, beneath the bearing 11, with a bevel pinion 17, rigidly mounted at one end of a horizontal shaft 18. The shaft 18 is rotatably supported in two lugs 19 and 20 depending from the frame 10. The hub of the pinion 17 abuts against one side of the lug 19, while the other side of the lug is engaged by a collar 21 fixed upon the shaft 18. Thus the shaft 18 is held against endwise movement. Shaft 18 receives its motion from drive pulley 22 through a clutch mechanism, which will be later described.

Interposed between bearing 11 and cam 13 is a pinion 23, rigidly mounted on shaft 100

12, to be driven thereby, the function of which will be later described.

A block or flange supporting drum 24 is mounted upon the cam member 13 and fastened there by bolts 25. Drum 24 comprises upstanding cylindrical walls 26 and an upper laterally extending flange 27, shaped as shown in Fig. 13, upon which the hat flanging block 31 rests. The wall 26 is preferably 10 formed with openings therethrough, as shown at 29 in Fig. 10. These save material and make the drum lighter.

Referring to Fig. 10, it will be seen that the flange 27 supports a hat flanging block 31. Hat flanges are commonly used with various types of flanging machines and hand devices to support hats which are to have their brims pressed to their ultimate shape or style, and are constructed with a central oval opening 28 into which the hat crown fits, with the brim overlying the top of the flange. The flange is formed with a peripheral edge at the top corresponding with the shape desired to be given to the finished hat in cases 25 where the hat brim is to be curled, as shown at 32, and is further made with a variable concavo-convex upper surface 33 adapted to produce the proper scope.

In carrying out my invention, a hat 34 is 30 fitted to such a block before the latter is placed in the machine. In fitting, the edge of the brim is bent down over the edge of the block, a covering of fabric material 36 is spread over all and stretched down over the 35 edge of the block. It is then drawn tightly into contact with a peripheral groove 37 formed in the block 31 by means of a cord 38, holding the hat brim firmly in place, with its brim curled to conform to the block. Before 40 placing on the machine, the hat brim is softened by steaming. The flanging block is provided with oppositely disposed openings 39 extending upwardly into the body thereof from its lower surface. When the block is 45 set upon the supporting drum 24, these openings fit loosely over positioning pins or pin levers 40 which are pivoted, as at 41, in brackets 42 provided on the periphery of the said drum. Beneath the pivots the pins 40 are 50 provided with downward extensions 43. Pockets 44 positioned in the inner sides of the pin extensions form seats for springs 45 interposed between said extensions and plates 46 secured upon the inner surface of the wall 26 55 and bridging narrow openings 47 formed in said walls, and through which the springs pass. These springs normally hold the heads of the pins 40 in toward the axis of the drum, in which position they are readily received 60 within the openings 39 in the hat flange as the latter is placed on the support.

At 48 is shown a hand wheel supported with an annular portion thereof 48', rotatably seated between the upper surface of the cam member 13 and the bottom of the drum 24.

The hand wheel is provided with a pair of upwardly extending segmental flanges 49, see Figs. 1, 10 and 13, concentrically surrounding a portion of the walls 26. Each of these flanges is provided with leaf springs 35 extending beyond an end thereof. The hand wheel may be turned about the axis of the block support in one direction until the springless ends of the flanges 49 engage respectively the pin extensions 43. This is 70 their inoperative position. After the hat block has been set over the pins, the hand wheel is revolved in the opposite direction, causing the springs 35 to ride over the pin extensions 43 to force them inwardly toward the axis of the support, against the resistances of springs 45. The pins are thus thrown outwardly to engage firmly against the walls of the openings with such force as to reliably hold the hat block in position. The movement of the hand wheel in the latter direction is also limited by the engagement of the ends of the segments with the pin extensions. 75

Before proceeding further with the detailed description of my machine, the operation which it is designed to perform should be clearly understood. One of the last operations performed on a felt hat is known as flanging. Its object is to press the brim to the final form which it is to assume in the finished hat and to permanently set the brim in that form. It has long been the established practice to accomplish this by placing the hat in a flanging block or flange of the desired size and shape, drawing the brim of the hat down tightly across and, in some cases, over the edge of the flange, and holding it in such position by covering the whole base of the hat, including head opening and brim, with a piece of flannel, which is stretched tightly over the edge of the hat flange and secured in place by means of a cord passed about a groove or channel formed in the flange for this purpose. The brim of the hat is then 90 softened by steaming, when hat and block are placed in a machine adapted to receive it with the bottom of the hat upturned. A heavy bag of heated sand is then lowered down upon the brim, when it is left to dry out. In this way, the brim is dried out under pressure so that when removed from the machine and block, it retains the desired form. It should here be noted, however, that by this old method, pressure is applied only to the bottom of the brim. When hats are to be flanged with curled or turned brims, in order to set the turned-over portions thereof, heated irons are applied thereto by hand, producing more or less satisfactory results, but at a considerable expenditure of labor. 100

It is one of the outstanding features of my invention that this manual stage in the process of flanging is done away with, by the use of the apparatus, in which the entire flanging operation is carried out in a single oper- 105 110 115 120 125 130

ation, which includes pressing with a heated iron that portion of the brim which overlies the flanging block, and simultaneously pressing with another iron that part of the brim which is turned over and under the periphery of the flange.

Referring to Figs. 1, 2, 3, 7 and 19, an upper flanging iron is shown at 50, and a lower flanging iron at 51. Iron 50 is freely pivoted, as at 52 and 53 (Fig. 7), between the arms 54 and 55 (Fig. 7) of a clevis having a cross member 56. Beyond the pivots 52 and 53 the arms 54 and 55 are extended upwardly at an angle, as shown at 57 and 58 in Fig. 3, and between the upper ends of these extensions is pivoted a shaft 59 (Fig. 7), having fixed substantially at the middle thereof a weight arm 60. Fixed at the ends of shaft 59 are a pair of cranks 61 and 62 (Fig. 3), extending generally in a direction opposite to that of the weight arm 60. A link 63 is pivoted adjacent the end of the crank 61, and a corresponding link 64 is pivoted adjacent the end of the crank 62 as most clearly shown in Fig. 3. These links extend downwardly and adjacent their lower ends are bent forwardly. Between these forwardly turned ends is journaled the lower flanging iron 51 (Figs. 1, 2 and 3).

Abutment members 67 and 68, formed upon the cranks 61 and 62, are adapted to engage the under sides of the links 63 and 64 (Figs. 3 and 7) to swing them rearwardly to the position shown in Fig. 19, when the weight arm is thrown forward to occupy the position C, shown in the same figure, and in dotted outline in Fig. 1. The weight arm is locked in its position C against rearward rotation by the engagement of a finger 69 (Fig. 3) of the trigger 70 with the cutaway radial edge 71 (Fig. 2) of a segmental abutment 72 formed upon the journal end portion of the arm 58 (see Figs. 2 and 3.) Trigger 70 is pivoted at 73 (Fig. 3) to the weight arm 60 and is movably held outwardly therefrom by the spring 74. When the trigger is pressed toward the weight arm, the finger 69 is raised so as to ride upon the periphery of segment 72.

Turning to Fig. 7, at the center of the cross member 56 of the clevis, there may be seen a hub or boss 75 formed upon the rear side of the cross arm. This hub engages the forward end of a sleeve 76, which forms a bearing for a shaft 77, formed as an integral part of the clevis, and extending rearwardly therefrom. Sleeve 76 is formed at the upper end of a swinging arm 78 (Fig. 1), which is itself pivoted at its lower end to the bracket 79 by means of the pin 80 having at one end a head 81 (Fig. 7), and threaded at its opposite end to receive a nut 82. The bracket 79 is secured to a movable carriage 83 (Figs. 1 and 2) by machine screws 84 (Fig. 7).

To the rear end of shaft 77 is secured a

collar 85 (Fig. 2) provided with a pair of spaced legs 86 adapted to engage upon either side of the swinging arm 78, to limit the pivotal movement of the clevis about the axis of shaft 77 and sleeve 76.

The swinging arm is limited in its rearward movement about the pin 80 by the engagement of a projection 87 formed upon its lower end with a part of the arm 78, as may be seen by reference to position D of said parts, as illustrated in broken lines in Fig. 1. An abutment 88, provided upon the under side of the swinging arm, engages a fixed abutment 89 (Figs. 1 and 2) raised upwardly from the carriage 83, when the latter has moved far enough to the left, as seen in the figures, to cause the iron 50 to fall over the edge of the hat brim. Likewise, the weight arm 60 is prevented from falling forward beyond a certain point by the rearward engagement of the lower flanging iron with the under side of the swinging arm.

Before continuing with the detailed description of my invention, it should be said here that the motion of the flanging irons relative to the axis of the hat block is the resultant of two distinct movements. The first of these movements is reciprocatory toward and away from the hat axis in order that the irons may continuously follow the oval of the hat and at the same time bear against the hat with a substantially uniform pressure, whether the point of contact be at an extremity of the long diameter of the oval, or at an extremity of the short diameter, or at some point therebetween.

The second movement of the irons is a traversing movement of the upper iron across the brim of the hat from its inner edge to its extreme outer edge, during the greater portion of which travel of the upper iron, the lower iron is drawn upwardly and outwardly to engage the brim of the hat, where it underlies the peripheral flange of the hat flanging block.

The manner of mounting the iron swinging arm in order to impart to it the movements described, will now be explained. The carriage 83 is rigidly mounted, as shown in Figs. 1, 2, 3, 4 and 6, upon a pair of rods 90, which are slidably supported in bearing lugs 91, forming a part of and rising above a movable table 92. Table 92 is slidably supported by means of downwardly extending slide bearings 93 upon a pair of guide rods 94, which are rigidly mounted, as shown, in pillow blocks 95 and 96, secured upon the frame 10. Thus the carriage 83 is mounted for reciprocal movement forward and back with respect to table 92, and the latter is similarly mounted with respect to the frame 10.

Table 92 further carries rotatably mounted in its downwardly extending bearing members 93 a feed screw 97, best seen in Figs. 130

1, 3, 5, 6 and 8. The screw has a shoulder, as at 98 (Fig. 1), which bears against the forward face of the rear bearing member 93. A

70 collar 99 is pinned to the rear end of said screw, and a thrust bearing 100 is interposed between said collar and the rear face of bearing member 93. Thus the screw is held immovable longitudinally with respect to

75 table 92. At its forward end, said screw is provided with a squared extension 101 having a sliding fit within a similarly shaped axial opening extending through the hub 102 of a bevel gear 103. This gear has its bearing

75 iron 50 so that the iron may follow the contour of the brim of the hat, stud 106 gradually feeds carriage 83 in a left hand direction (Figure 1) toward the edge of the hat until the parts reach the position shown in Figure 19.

80 The clutch mechanism for engaging and disengaging the drive pulley 22 with the shaft 18 will now be described. The pulley is rotatably mounted on said shaft and has limited movement longitudinally thereof between a movable collar 117 and a fixed collar 118. The latter is provided with a forwardly extending lug 119 adapted to engage a rearwardly extending lug 120 formed upon the hub of the pulley and, when so engaged, to rotate the shaft 18, when the pulley is turned. No means is shown in the drawings for rotating the pulley, but it will be understood that this may be accomplished by means of belting to any suitable source of power. A spring 121, interposed between the fixed collar and pulley, normally hold them out of operative engagement one with the other, when the movable collar 117 is oscillated to such a position as to permit the registration of a cam projection 122 formed upon the forward face thereof with a recess 123 provided in the rear surface of the bearing member 20.

85 In order to accomplish the reciprocatory movement of the traversing mechanism to accommodate the position of the flanging iron to the oval shape of the hat brim, a bracket 114 is formed upon or fastened to the forward end of the table 92 (Figs. 1 and 2). This bracket has rotatably mounted thereon

90 a pair of cam rollers 115 and 116 disposed in a position closely to engage between their peripheries the downwardly extending wall 14 of the cam member 13.

95 Accordingly, upon rotation of cam 13 by way of shaft 11, rollers 115 and 116, follow-

100 ing the contour of cam 13, reciprocate table 92, by way of bracket 114, forwardly and rearwardly, preferably twice in each direction during each revolution of the cam member.

105 As pointed out above, shaft 97 is secured to table 92 against relative motion with respect to the table but is slidably connected to stationary bevel gear 103 so that it reciprocates with table 92. Stud 106 and

110 nut 107 form a direct connection between shaft 97 and carriage 83, but, when cam 13 is rotating, shaft 97 is likewise rotating so that stud 106 and carriage 83 are fed in a left hand direction. Therefore, while rolls

115 114 and 115 coat with cam 13 during the rotation of the hat block to impart reciprocatory motion to carriage 83 and consequently

120 iron 50 so that the iron may follow the contour of the brim of the hat, stud 106 gradually feeds carriage 83 in a left hand direction (Figure 1) toward the edge of the hat until the parts reach the position shown in Figure 19.

125 The clutch mechanism for engaging and disengaging the drive pulley 22 with the shaft 18 will now be described. The pulley is rotatably mounted on said shaft and has limited movement longitudinally thereof between a movable collar 117 and a fixed collar 118. The latter is provided with a forwardly

130 extending lug 119 adapted to engage a rearwardly extending lug 120 formed upon the hub of the pulley and, when so engaged, to rotate the shaft 18, when the pulley is turned. No means is shown in the drawings for rotating the pulley, but it will be understood that this may be accomplished by means of belting to any suitable source of power. A

135 spring 121, interposed between the fixed collar and pulley, normally hold them out of operative engagement one with the other, when the movable collar 117 is oscillated to such a position as to permit the registration of a cam projection 122 formed upon the forward face thereof with a recess 123 provided in the rear surface of the bearing member 20.

140 This oscillation is performed by the engagement with a pin 124 (Figs. 1 and 7) secured to extend outwardly in a radial direction from the surface of the collar 117, of the lower laterally extending crank arm 125 of the crank shaft 126, journaled in the vertical

145 bearing 127 provided upon the frame 10. At its upper end, the said crank shaft carries an offset crank arm 128 adapted to be thrown, when the carriage 83 is in its rearmost position, by contact with a bolt or other abutment 129, projecting downwardly from said

150 carriage adjacent the rear end thereof. When thus thrown, the collar 117 is turned to cause the registry of parts 122 and 123, when the collar 117 moves to the right and the clutch parts 119 and 120, becoming disengaged, the

155 pulley runs idly upon the shaft 18, at which

time all movements of the apparatus cease. To restart the machine, the carriage 83 is moved forward by the operator in the manner hereinbefore described, after which, he 5 resets the collar by turning it by means of the handle 130 (Fig. 4), provided for that purpose, until the cam projection 122 rides out of the recess 123 to the position shown in the drawings, when the clutch parts re-engage 10 to drive the shaft 18, and thereby set in motion all of the driven parts coupled therewith.

The upper flanging iron 50 is journaled between the yoke arms by means of the solid bolt 131 and the hollow bolt 132 (see Fig. 10), which enter threaded holes oppositely positioned in the sides of the iron. The hole receiving the bolt 132 is continued beyond the end of the bolt to form the recess 133 for holding the heating element 134. This is 15 preferably an electrical heating unit, connected with which is an insulated cable 135 containing the wires which supply the unit with current. The cable may have connection at its free end, in any suitable manner, 20 with a suitable source of electric energy. In form, the iron 50 is substantially rectangular, and the pivotal parts are in line with its transverse axis. At 136 (Fig. 1), I show some of the metal removed from its front 25 face, producing a cavity therein. This serves to lighten that part of the iron forwardly of the pivots so that the rear portion of the iron may the more readily follow the downward slope of the brim as its edge is approached. 30 Also, the bottom face of the iron is made somewhat convex in order the more readily to conform to the scope of the rotating hat upon 35 which it rests when in operation.

By reference to Figs. 14 to 18, it will be 40 seen that the lower flanging iron 51 comprises a solid body portion 137, a detachable shoe 138, a semi-cylindrical cover plate 139, and a heating unit 140.

The heating unit may be an electric heater 45 similar to that used in the upper iron, held in place against the back of the body portion 137 by means of the cover plate 139. The latter is fastened to the body by means of screws 141. The body portion 137, best seen 50 in Fig. 16, is provided with a projecting part 142, recessed as at 143 to receive a tenon 144 formed at an end of the shoe 138. To assemble the shoe upon the body portion, the tenon 144 is first entered within the recess 143, after 55 which the two parts are pressed together, until their corresponding faces meet. The connection is then made fast by means of a thumb screw 145 threaded into the part 137 and adapted to take into the threaded hole 146 provided for that purpose in the shoe. An upstanding part 147 takes over the end 60 of the shoe more securely to hold it in place.

Upon either side of the iron body 137 are 65 trunnion members 148, against the end surfaces of which the links 63 and 64 are pivot-

ally secured by means of bolts 149 (see Fig. 9).

Figs. 11 and 12 illustrate a modified form of shoe having a curved fin 150 projecting outwardly from the upper surface of the shoe. 70 This form of shoe is employed when the hat to be operated upon is to be flanged to a shape having very decided curvature at the edge of the hat flange with the part underlying the flange disposed more nearly parallel to 75 that part of the brim overlying the flange. With such a form it is impossible to cover the whole surface of the curled brim with a plain faced lower iron in conjunction with the upper iron. This difficulty is, however, fully 80 removed when the modified form of lower iron is employed.

Having now described the general construction and the interrelation of the various parts of the present embodiment of my invention, its mode of operation will be briefly outlined. Let it be supposed that the drive pulley clutch is in its inoperative position with the swing arm 78 thrown off at its D position, as seen in Fig. 1. The operator will 85 place upon the hat block support 26, a hat flanging block upon which a hat has been stretched, in the position shown in the figure. He will then lock the block in position by revolving the wheel 48 in the manner hereinbefore described. If the electrical current has been turned on so as to supply the heating units of the two flanging irons, they will 90 be hot and ready for use. The collar 117 is now turned to force the clutch parts into 95 interlocking relation when the shaft 18 begins to rotate, causing the shaft 12 and the parts secured thereto to rotate at a slower rate, which rate depends upon the relative 100 diameters of the bevel gears 15 and 17. 105 Grasping the handle 113 and lever 108, he releases the nut 107 from the feed screw and slides the carriage 83 forward to its innermost position, releases the lever 108 to bring 110 the nut into operative relation with the feed screw, then throws the swinging arm forward to the position shown in solid lines in Fig. 1, with the weight arm leaning slightly back from a vertical position, the frictional contact of the trigger finger 69 with the periphery of the segment 72 being sufficient to retain the parts, as shown.

The hat block and hat are now turning about their vertical axis, together with the cam 13. The rotation of cam 13 immediately starts the slow reciprocatory movement of the table 92, the carriage 83, the swinging arm 78, and the flanging irons 50 and 51, whereby the said irons are 115 positively moved toward and away from the axis of the hat in order that the irons may follow the contour of the hat brim smoothly and with substantially uniform pressure. Simultaneously, the feed screw 120 commences to turn to feed the carriage 83 125 130

progressively in a rearward direction, carrying with it swinging arm and upper iron 50, the latter slowly making its traverse across the brim of the hat from head opening to outer edge. The lower iron does not, however, follow this course of traverse, for, by reason of its link connections with the shaft supporting the weight arm 60, any tendency which it may have to draw away 10 from the hat flanging block is offset by the gradual descent rearwardly of the said weight arm and consequent forward advancement of the lower iron. When the traverse has proceeded to the point shown in Fig. 2, 15 the weight arm has descended to the position shown in that figure and the upper iron is about to fall or turn over the edge of the hat brim. At this point the lower iron must be drawn back out of the way so that the upper iron can tilt downwardly, as shown in Fig. 19. The operator at this stage in the operation of the apparatus, grasps the weight lever and swings it forward to the position shown in Fig. 19, retracting the lower iron to the 20 position shown in the same figure.

A little more rearward traverse, and the upper iron is drawn clear of the hat brim, the swinging arm comes to rest in contact with the stop 89 (Fig. 19), the abutment bolt 129 engages the crank 128 of the crank lever 126, and the lower crank 125, meeting the pin 124, oscillates the collar 117, to release the clutch members 119 and 120 and to stop the machine. The swing arm is now drawn back to its position D shown in broken lines Figure 1, and the apparatus is ready to receive another hat flange and hat.

It should here be explained that, because of the curvature of the hat brim, the irons bear thereon over very limited areas of contact. In order that they may conform to the varying curvatures of these small areas of contact and at the same time accommodate themselves to the varying contour of the scope of the hat, both irons are pivoted to turn freely about their transverse axes, and both together turn with the clevis about its swivel connection with the swinging arm. The irons may also move up and down, by reason of the pivotal mounting of the swinging arm upon the carriage, and thus follow the changing curvatures of the brim due to its scope.

It should also be understood that it is not necessary to employ the lower iron in cases where the hat to be flanged is to have very little curl given to the brim. In such a case, the lower iron is retained in its retracted position throughout the entire flanging operation, the upper iron operating alone in the same manner as has been described, when the lower iron co-operates with it to complete the flanging of the underlying portion of the hat brim.

From the foregoing it will be seen that my

invention marks an important achievement in the art from which many outstanding advantageous results accrue. Among these may be noted an economy of labor and a quantity of output not possible of attainment by the methods heretofore employed. The use of uniformly and continuously heated irons produces in itself a saving of time, for it was necessary frequently to reheat the sand bags formerly employed, and the simultaneous operations upon the upper and lower surfaces of the turned brim not only eliminate a manually performed stage in the process of flanging, but give far more uniform results. The machine of my invention, as herein described, is simple of construction, easily operated, and ruggedly built to withstand long usage. Thus it will be seen that it is well adapted to attain all of the ends and objects of my invention.

As various embodiments might be made of this invention, and as various changes might be made in the construction herein described, all without departing from the scope of the invention, it is to be understood that all matter herein set forth or shown in the accompanying drawings is to be interpreted as illustrative and not in a limiting sense.

I claim:

1. In a hat flanging machine, in combination, means adapted to support a hat block, a hat block having a peripheral flange over which the brim of a hat is fitted, means for rotating said block supporting means, and an upper and a lower iron adapted respectively to operate on different portions of the same surface of the hat brim and positioned above and below the peripheral edge of said flange.

2. In a hat flanging machine, in combination, means adapted to support a hat block, a hat block having a peripheral flange over which the brim of a hat is fitted, means for rotating said block supporting means, an upper and a lower iron adapted respectively to operate on different portions of the same surface of the hat brim and positioned above and below the peripheral edge of said flange, and means mounting said irons for movement toward and away from the axis of said block supporting means.

3. In a hat flanging machine, in combination, means adapted to support a hat block, a hat block having a peripheral flange over which the brim of a hat is fitted, means for rotating said block supporting means, an upper and a lower iron adapted respectively to operate on different portions of the same surface of the hat brim and positioned above and below the peripheral edge of said flange, means mounting said irons for movement toward and away from the axis of said block supporting means, and means for giving to said mounting means a controlled reciprocatory movement.

4. In a hat flanging machine, in combina-

tion, means adapted to support a hat block, a hat block having a peripheral flange over which the brim of a hat is fitted, means for rotating said block supporting means, an upper and a lower iron adapted respectively to operate on portions of the hat brim positioned above and below the peripheral edge of said flange, means mounting said irons for movement toward and away from the axis of said block supporting means, and means for feeding said mounting means away from the axis of said block supporting means to cause said upper iron to traverse the brim of the hat.

5. In a hat flanging machine, in combination, means adapted to support a hat block, a hat block having a peripheral flange over which the brim of a hat is fitted, means for rotating said block supporting means, an upper and a lower iron adapted respectively to operate on portions of the hat brim positioned above and below the peripheral edge of said flange, means mounting said irons for movement toward and away from the axis of said block supporting means, means for 10 giving to said mounting means a controlled reciprocatory movement, and means for feeding said mounting means away from the axis of said block supporting means to cause said upper iron to traverse the brim of the hat.

20. 6. In a hat flanging machine, in combination, means adapted to support a hat block, a hat block having a supporting surface upon which the brim of a hat may rest, means for rotating said block supporting means, an iron adapted to operate on a part of the brim overlying said surface, and power driven means adapted to cause said iron to traverse said brim in one direction from the inner to the outer edge thereof, said means being operatively responsive to the rotation of said block.

25. 7. In a hat flanging machine, in combination, means adapted to support a hat block, a hat block having a supporting surface for the brim of a hat, means for rotating said block supporting means, a slidably mounted carriage, an arm pivotally mounted on said carriage and adapted to be swung into and out of operative position relative to said hat block support, an iron pivotally mounted on said arm, and means for actuating said carriage to cause said iron to traverse a portion of said hat brim.

30. 8. In a hat flanging machine, in combination, means adapted to support a hat block, a hat block having a supporting surface for the brim of a hat, means for rotating said block supporting means, a slidably mounted carriage, an arm pivotally mounted on said carriage and adapted to be swung into and out of operative position relative to said hat block support, an iron mounted on said arm, a screw for feeding said carriage to cause said iron to traverse a portion of said hat brim, and means operatively responsive to

the rotation of said hat block supporting means for turning said screw upon rotation of said hat block support.

9. In a hat flanging machine, in combination, means adapted to support a hat block, a hat block having a supporting surface for the brim of a hat, means for rotating said block supporting means, a slidably mounted carriage, an arm pivotally mounted on said carriage and adapted to be swung into and out of operative position relative to said hat block support, an iron mounted on said arm, a slidably mounted table upon which said carriage is mounted, a feed screw rotatably mounted on said table, driving means for said screw, and means upon said carriage meshing with said screw to move said carriage and to limit the relative movement between said carriage and table to movement resulting from said coaction.

10. In a hat flanging machine, in combination, means adapted to support a hat block, a hat block having a supporting surface for the brim of a hat, means for rotating said block supporting means, a slidably mounted carriage, an arm pivotally mounted on said carriage and adapted to be swung into and out of operative position relative to said hat block support, an iron mounted on said arm, a slidably mounted table upon which said carriage is mounted, a feed screw rotatably mounted on said table, driving means for said screw, means upon said carriage meshing with said screw to move said carriage and to limit the relative movement between said carriage and table to movement resulting from said coaction, a cam mounted on said hat block support and rotatable therewith, and means for causing reciprocation of said table and said carriage by actuation of said cam.

11. In a hat flanging machine, in combination, means adapted to support a hat block, a hat block having a supporting surface for the brim of a hat, means for rotating said block supporting means, a slidably mounted carriage, an arm pivotally mounted on said carriage and adapted to be swung into and out of operative position relative to said hat block support, an iron mounted on said arm, a slidably mounted table upon which said carriage is mounted, a feed screw rotatably mounted on said table, and means upon said carriage adapted to coact with said screw to move said carriage and to limit the relative movement between said carriage and table to movement resulting from said coaction, said coacting means being manually movable into and out of engagement with said screw.

12. In a hat flanging machine, in combination, a frame, a rotating hat block support mounted in said frame, an iron adapted to operate upon the brim of a hat carried by said block support, mounting means for said iron adapted to impart thereto a straight line

- movement relative to said hat comprising two relatively movable members, one of which is movably mounted on said frame, a gear rotatably mounted on said frame, a gear meshing therewith and rotatable with said block support, a screw rotatably mounted on said one member and slidably mounted in said first gear, said screw being adapted to be rotated by said gear, and a nut mounted upon said other member adapted to lock said two members against relative movement and to cause progressive movement of said one member relative to said other member when said screw is rotated.
13. In a hat flanging machine, in combination, a frame, a rotating hat block support mounted in said frame, an iron adapted to operate upon the brim of a hat carried by said block support, mounting means for said iron adapted to impart thereto a straight line movement relative to said hat comprising two relatively movable members, one of which is movably mounted on said frame, a gear rotatably mounted on said frame, a gear meshing therewith and rotatable with said block support, a screw rotatably mounted on said one member and slidably mounted in said first gear, said screw being adapted to be rotated by said gear, a nut mounted upon said other member adapted to lock said two members against relative movement and to cause progressive movement of said one member relative to said other member when said screw is rotated, and means for disengaging said nut from said screw to permit free relative movement of said two members.
14. In a hat flanging machine, in combination, a frame, a rotating hat block support mounted in said frame, an iron adapted to operate upon the brim of a hat carried by said block support, mounting means for said iron adapted to impart thereto a straight line movement relative to said hat comprising two relatively movable members, one of which is movably mounted on said frame, a cam mounted upon and rotatable with said hat block support, releasable means for locking said movable members against relative movement, and cam-engaging means mounted upon one of said members adapted to be actuated by said cam to give to said two members a controlled reciprocatory motion.
15. In a hat flanging machine, in combination, a frame, a rotating hat block support mounted in said frame, an iron adapted to operate upon the brim of a hat carried by said block support, mounting means for said iron adapted to impart thereto a straight line movement relative to said hat comprising two relatively movable members, a gear rotatably mounted on said frame, a gear meshing therewith and rotatable with said block support, a screw rotatably mounted on said one member and slidably mounted in said first gear, said screw being adapted to be rotated by

said gear, a nut mounted upon said other member adapted to lock said two members against relative movement and to cause progressive movement of said one member relative to said other member when said screw is rotated, a cam mounted upon and rotatable with said hat block support, and cam-engaging means mounted upon said one member and adapted to be actuated by said cam to give to said two members a controlled reciprocatory motion toward and away from said hat block support.

16. In a hat flanging machine, in combination, means having a surface upon which the brim of a hat may rest, a supporting member, an iron mounted upon said supporting member and adapted to operate on a portion of said hat brim, and a second iron positioned below said first iron and mounted upon said supporting member to swing about a part thereof positioned above said first iron.

17. In a hat flanging machine, in combination, means having a surface upon which the brim of a hat may rest, a supporting member, an iron mounted upon said supporting member and adapted to operate on a portion of said hat brim, a second iron positioned below said first iron and mounted upon said supporting member to swing about a part thereof positioned above said first iron, and means adapted to hold said second iron in operative engagement with said hat brim.

18. In a hat flanging machine, in combination, means having a surface upon which the brim of a hat may rest, a supporting member, an iron mounted upon said supporting member and adapted to operate on a portion of said hat brim, a second iron positioned below said first iron and mounted upon said supporting member to swing about a part thereof positioned above said first iron, means adapted to hold said second iron in operative engagement with said hat brim, and means associated with said last means for withdrawing said second iron to an inoperative position.

19. In a hat flanging machine, in combination, a supporting member, a clevis mounted to swivel therein, and an iron pivotally mounted in said clevis to rock about an axis disposed substantially at right angles to the swivel axis, the mass of said iron at one side of its axis being greater than the mass thereon upon the other side of said axis to produce a tendency in said iron to swing downwardly upon the said one side of the axis.

20. In a hat flanging machine, in combination, means having a surface upon which the brim of a hat may rest, a supporting member, an iron mounted upon said supporting member and adapted to operate on a portion of said hat brim, a second iron positioned below said first iron and mounted upon said supporting member to swing about a part thereof positioned above said

first iron, and means for heating both of said irons.

21. In a hat flanging machine, in combination, a supporting member, a clevis mounted to swivel thereon, an iron pivotally mounted in said clevis, a crank pivotally mounted in said clevis, a second iron suspended below said first iron from said crank, and a weight arm associated with said crank tending normally to lift said second iron toward said first iron. 70

22. In a hat flanging machine, in combination, a supporting member, a clevis mounted to swivel thereon, an iron pivotally mounted in said clevis, a crank pivotally mounted in said clevis, a second iron suspended below said first iron from said crank, a weight arm associated with said crank tending normally to lift said second iron toward said first iron, and means associated with said crank adapted, when said weight arm is moved to a certain position, to move said second iron to an inoperative position. 80

23. In a hat flanging machine, in combination, a frame, means having a surface upon which the brim of a hat may rest, a member slidably mounted on said frame, a swinging arm pivotally mounted on said member, adapted to swing toward or away from said block supporting means into operative or inoperative position, a clevis swiveled in said swinging arm, an iron pivotally mounted in said clevis, a pair of crank members pivotally mounted in said clevis at a point above and forwardly of said iron, a pair of links journaled upon said crank members and extending downwardly therefrom to a point below said iron, a second iron pivotally mounted between said links, means associated with said cranks adapted to engage the under sides of said links to force said second iron into an inoperative position, and means for locking said parts in said inoperative position. 90

24. In a hat flanging machine, in combination, a frame, means forming a supporting surface for the brim of a hat, a member slidably mounted on said frame, a swinging arm pivotally mounted on said member, adapted to swing toward or away from said block supporting means into operative or inoperative position, a clevis swiveled in said swinging arm, an iron pivotally mounted in said clevis, a pair of crank members pivotally mounted in said clevis at a point above and forwardly of said iron, a pair of links journaled upon said crank members and extending downwardly therefrom to a point below said iron, a second iron pivotally mounted between said links, and means adapted to limit the swiveling movement of said clevis. 100

25. In a hat flanging machine, in combination, a frame, a member mounted on said frame to move along a straight line path, an arm mounted on said member for pivotal movement about an axis substantially at right angles to said straight line path, an iron support mounted upon said arm for swiveling movement about an axis substantially parallel with said straight line path, and an iron mounted on said support for pivotal movement about an axis substantially at right angles to said straight line path. 110

26. In a hat flanging machine, in combination, a frame, means forming a supporting surface for the brim of a hat, a member slidably mounted on said frame, a swinging arm pivotally mounted on said member, adapted to swing toward or away from said block supporting means into operative or 120

65

inoperative position, a clevis swiveled in said swinging arm, an iron pivotally mounted in said clevis, a pair of crank members pivotally mounted in said clevis at a point above and forwardly of said iron, a pair of links journaled upon said crank members and extending downwardly therefrom to a point below said iron, a second iron pivotally mounted between said links, and means associated with said cranks adapted to engage the under sides of said links to force said second iron into an inoperative position. 75

27. In a hat flanging machine, in combination, a frame, means forming a supporting surface for the brim of a hat, a member slidably mounted on said frame, a swinging arm pivotally mounted on said member, adapted to swing toward or away from said block supporting means into operative or inoperative position, a clevis swiveled in said swinging arm, an iron pivotally mounted in said clevis, a pair of crank members pivotally mounted in said clevis at a point above and forwardly of said iron, a pair of links journaled upon said crank members and extending downwardly therefrom to a point below said iron, a second iron pivotally mounted between said links, means associated with said cranks adapted to engage the under sides of said links to force said second iron into an inoperative position, and means for locking said parts in said inoperative position. 85

28. In a hat flanging machine, in combination, a frame, a member mounted on said frame to move along a straight line path, an arm mounted on said member for pivotal movement about an axis substantially at right angles to said straight line path, an iron support mounted upon said arm for swiveling movement about an axis substantially parallel with said straight line path, and an iron mounted on said support for pivotal movement about an axis substantially at right angles to said straight line path. 105

29. In a hat flanging machine, in combination, a frame, a member mounted on said frame to move along a straight line path, an arm mounted on said member for pivotal 110

130

- movement about an axis substantially at right angles to said straight line path, an iron support mounted upon said arm for swiveling movement about an axis substantially parallel with said straight line path, and a pair of coacting irons each mounted upon said support for pivotal movement about an axis substantially at right angles to said straight line path.
30. In a hat flanging machine, in combination, means adapted to support a hat block, a hat block having a supporting surface upon which the brim of a hat may rest, an iron supporting member, a flanging iron comprising a body portion adapted to be pivotally mounted upon said supporting member, a shoe member having a surface form adapted to operate on that part of the hat brim which underlies the peripheral edge of the flanging block,
- 15 and means for holding said shoe member upon said body portion.
31. In a hat flanging machine, in combination, means adapted to support a hat block, a hat block having a supporting surface upon which the brim of a hat may rest, an iron supporting member, a flanging iron comprising a body portion adapted to be pivotally mounted upon said supporting member, a shoe member having a surface form adapted
- 20 to operate on that part of the hat brim which underlies the peripheral edge of the flanging block, means for holding said shoe member upon said body portion, and an electrical heating unit removably mounted upon said
- 25 body portion.
32. In a hat flanging machine, in combination, a hat block, means adapted to support said hat block, said block having a supporting surface over which the brim of a hat
- 30 may be fitted, means for rotating said supporting means, a supporting member, a clevis mounted on said supporting member, an iron pivotally mounted in said clevis, the mass of said iron on one side of the axis of said pivot
- 35 being greater than the mass thereof upon the other side of said axis, and means for feeding said supporting member away from the axis of said block to cause said iron to traverse the brim of said hat.
33. In a hat flanging machine, in combination, a hat block support, a hat flanging block adapted to rest on said support, a plurality of recesses in said block, pin levers pivotally connected to said support and extending above the upper surface thereof to register with and extend into said recesses when said block rests upon said support, and a rotatable cam member mounted upon said support having its cam surface directly engaging said levers to force said levers into gripping engagement with said block.
34. In a hat flanging machine, in combination, means adapted to support a hat block, a hat block having a peripheral flange
- 35 upon which the brim of a hat may be sup-
- ported, means for rotating said block supporting means, an iron shaped to rest against the under side of said flange, and means for supporting said iron against the under side of said flange when said block is rotating.
35. In a hat flanging machine, in combination, means adapted to support a hat block, a hat block having a peripheral flange upon which the brim of a hat may be supported, means for rotating said block supporting means, an iron, means for supporting said iron against the under side of said flange when said block is rotating, and reciprocating means for moving said iron toward and away from the axis of said block supporting means.
36. In a hat flanging machine, in combination, means adapted to support a hat block, a hat block having a peripheral flange upon which the brim of a hat may be supported, means for rotating said block supporting means, an iron, means for supporting the said iron against the under side of said flange, reciprocating means for moving said iron toward and away from the axis of said block supporting means, and means actuated in conformity with the oval of the hat for controlling the stroke of said reciprocating means.
37. In a hat flanging machine, in combination, means adapted to support a hat block, a hat block having a peripheral flange upon which the brim of a hat may be supported, means for rotating said block supporting means, an iron means for supporting said iron in an operating position on the top of said flange, means adapted to cause said iron to traverse said brim from the inner to the outer edge thereof, a second iron operatively associated with said first iron, and means for supporting said second iron in engagement with the under side of said flange.
38. In a hat flanging machine, in combination, means adapted to support a hat block, a hat block having a peripheral flange upon which the brim of a hat may be supported, means for rotating said block supporting means, an iron, means for supporting said iron upon the upper side of said flange, means adapted to cause said iron to traverse said brim from the inner to the outer edge thereof, a second iron, and means for supporting said second iron in an operative position in engagement with the under side of said flange, said means being capable of holding said last-mentioned iron in engagement with said flange during the traverse of first-mentioned iron.
39. In a hat flanging machine, in combination, means adapted to support a hat block, a hat block having a peripheral flange upon which the brim of a hat may be supported, means for rotating said block sup-

porting means, an iron, means for supporting said iron on a part of the brim overlying said flange, means adapted to cause said iron to traverse said brim from the inner 5 to the outer edge thereof, a second iron, means for holding said second iron in operative engagement with a portion of the brim resting on the under side of said flange during the traverse of said first-mentioned 10 iron, and means adapted to disengage said second-mentioned iron from said brim during the traverse of said first-mentioned iron.

40. In a hat flanging machine, in combination, means adapted to support a hat block, a hat block having a peripheral flange upon which the brim of a hat may be supported, means for rotating said block supporting means, an iron, means for supporting said iron on a part of the brim overlying 15 said flange, means adapted to cause said iron to traverse said brim from the inner to the outer edge thereof, a second iron, means for holding said second iron in operative engagement with a portion of the brim resting on the under side of said flange during the traverse of said first-mentioned 20 iron, means adapted to disengage said second-mentioned iron from said brim during the traverse of said first-mentioned iron, and means for giving both of said irons a controlled reciprocal movement towards and away from the axis of the block supporting 25 means.

41. In a hat flanging machine, in combination, a supporting member, a member mounted to swivel thereon, and an iron pivotally mounted upon said last-mentioned member on an axis substantially at right angles to the axis of said swivel tending normally to swing downwardly upon one 30 side of its pivotal axis.

42. In a hat flanging machine, in combination, a hat block support, a hat flanging block adapted to rest on said support, a plurality of 45 recesses in said block, pin levers pivotally connected to said support, the portions of said pin levers on one side of said pivotal connections extending above the upper surface of said support to register with and extend 50 into said recesses when said block rests upon said support, and a rotatable cam member mounted upon said support and adapted to be turned to press against the portions of said levers on the other side of the said pivotal 55 connections from said first-mentioned portions to force said levers into gripping engagement with said block.

43. In a hat flanging machine, in combination, rotatable means forming a support for the brim of a hat, an iron adapted to operate on one portion of said brim, an iron adapted to operate on another portion of said 60 brim, means for reciprocating both of said irons in directions toward and away from the 65 axis of said supporting means when said sup-

porting means is rotating, and means for gradually feeding said first-mentioned iron away from the axis of said supporting means independently of said second-mentioned iron.

44. In a hat flanging machine, in combination, rotatable means forming a support for the brim of a hat, an iron adapted to operate on one portion of said brim, an iron adapted to operate on another portion of said brim, means for reciprocating both of said irons in 70 directions toward and away from the axis of said supporting means when said supporting means is rotating, means for gradually feeding said first-mentioned iron away from the axis of said supporting means, and means for holding said second-mentioned iron in contact with said second-mentioned portion of said brim during the operation of said last-mentioned means.

45. In a hat flanging machine, in combination, means forming a supporting surface for the brim of a hat, means for rotating said supporting means, a slidably mounted carriage, an arm mounted on said carriage, an iron pivotally mounted on said arm, and means operatively related to said second-mentioned means for feeding said carriage in a direction away from the axis of said supporting 85 means.

46. In a hat flanging machine, in combination, means forming a supporting surface for the brim of a hat, means for rotating said supporting means, a slidably mounted carriage, an arm mounted on said carriage, an iron pivotally mounted on said arm, means operatively related to said second-mentioned means for feeding said carriage in a direction away from the axis of said supporting means, and means for stopping the action of said last-mentioned means when said last-mentioned means reaches a certain position.

47. In a hat flanging machine, in combination, a supporting member, a clevis associated with said supporting member, an iron pivotally mounted in said clevis, crank means pivotally mounted in said clevis, a second iron suspended below said first iron from said crank means, and means associated with said crank means tending normally to lift said second-mentioned iron substantially toward 100 said first-mentioned iron.

48. In a hat flanging machine, in combination, a supporting member, a clevis associated with said supporting member, an iron pivotally mounted in said clevis, crank means pivotally mounted in said clevis, a second iron suspended below said first iron from 110 said crank means, and means associated with said crank means adapted to lift said second iron toward said first iron when in one position and adapted to move said second iron to an inoperative position when in another position.

49. In a hat flanging machine, in combination, a supporting member, a clevis mount-

ed on said supporting member, an iron pivotally mounted in said clevis, the mass of said iron at one side of its axis being greater than the mass thereon upon the other side of said axis, crank means mounted on said clevis, and a second iron suspended below said first iron from said crank means.

50. In a hat flanging machine, in combination, a frame, means forming a supporting surface for the brim of a hat, a member slidably mounted on said frame, a clevis secured to said member, an iron pivotally mounted in said clevis and adapted to engage one portion of said brim, crank means associated with said clevis, a second iron supported by said crank means, and means adapted to hold said second iron in engagement with another portion of the brim of said hat.

51. In a hat flanging machine, in combination, a frame, means forming a supporting surface for the brim of a hat, a member slidably mounted on said frame, a clevis secured to said member, an iron pivotally mounted in said clevis and adapted to engage one portion of said brim, crank means associated with said clevis, a second iron supported by said crank means, and means adapted to hold said second iron in engagement with another portion of the brim of said hat.

52. In a hat flanging machine, in combination, a frame, means forming a supporting surface for the brim of a hat, a member slidably mounted on said frame, a clevis secured to said member, an iron pivotally mounted in said clevis and adapted to engage one portion of said brim, crank means associated with said clevis, a second iron supported by said crank means, and means operatively associated with said crank means adapted to hold said second-mentioned iron against another portion of said brim when in one position and adapted to hold said second-mentioned iron out of engagement with said brim when in another position.

53. In a hat flanging machine, in combination, a frame, a hat block having an annular peripheral flange and supporting surface over which the brim of a hat may be fitted, rotatable means for holding said hat block, a member capable of relative motion with respect to said frame, a swinging arm pivotally mounted on said member and adapted to swing toward or away from said hat block into operative or inoperative positions, a clevis secured to said arm, an iron mounted in said clevis, a second iron, crank means secured to said clevis and adapted to support said second iron, and means for holding said second iron against substantially the under side of said flange.

54. In a hat flanging machine, in combination, a frame, a hat block having an annular peripheral flange and supporting surface over which the brim of a hat may be fitted, rotatable means for holding said hat block, a member capable of relative motion with respect to said frame, a swinging arm pivotally mounted on said member and adapted to swing toward or away from said hat block into operative or inoperative positions, a clevis secured to said arm, an iron mounted in said clevis, a second iron, crank means secured to said clevis and adapted to support said second iron, and means for holding said second-mentioned iron either in engagement with the under side of said flange or out of engagement therewith.

In testimony whereof, I have signed my name to this specification this 5th day of April, 1929.

STEPHEN J. MILLER.
